UNITED STATES PATENT OFFICE.

WILLIAM SHERMAN FLICK, OF ANDERSON, INDIANA, ASSIGNOR OF ONE-HALF TO
G. A. LAMBERT, OF ANDERSON, INDIANA.

GATE-OPENING DEVICE.

1,210,447.

Specification of Letters Patent. Patented Jan. 2, 1917.

Application filed January 28, 1916. Serial No. 74,810.

To all whom it may concern:

Be it known that I, WILLIAM SHERMAN FLICK, a citizen of the United States, residing at Anderson, in the county of Madison and State of Indiana, have invented certain new and useful Improvements in Gate-Opening Devices; and I do hereby declare the following to be a full, clear, and exact description of the invention, such as will enable others skilled in the art to which it appertains to make and use the same.

My invention relates to new and useful improvements in gate opening devices, and my object is to provide a hinge rod and so construct the same that when given a partial rotation the gate attached thereto will be caused to swing to an open or closed position.

A further object is to provide means on the end of the hinge rod for engagement with a pull cable for operating the hinge rod.

A further object is to extend the pull cable to either side of the gate structure and attach the ends thereof to levers whereby the gate may be opened from either side thereof. And a further object is to provide keepers for engagement with the gate latch to hold the gate in open position, the levers for operating the pull cable being pivotally attached to said keepers.

Other objects and advantages will be hereinafter set forth and more particularly pointed out in the accompanying specification.

In the accompanying drawings which are made a part of this application, Figure 1 is a perspective view of a section of a fence structure showing a gate and my improved operating means attached thereto. Fig. 2 is a top plan view of the hinge rod for the gate and pull cable coöperating therewith. Fig. 3 is a view similar to Fig. 1 showing a different form of device for rotating the hinge rod, and Fig. 4 is a detail perspective view of the upper end of that form of hinge rod and parts attached thereto shown in Fig. 3.

Referring to the drawings in which similar reference numerals designate corresponding parts throughout the several views, 1 and 2 indicate posts, such as are commonly employed in fence structures for supporting gates, the post 1 acting as the hinge post, while the post 2 serves as a latch-

ing post. Coöperating with the post 1 is a hinge rod 3, said rod extending through eyes 4 and 5 secured to the post 1 by threading the stems of the eyes and engaging nuts 4' and 5' therewith, said hinge rod having upper and lower crank portions 6 and 7 which are adjacent the eyes 4 and 5 respectively, the crank portion 6 extending in a diametrically opposite direction from the crank portion 7.

A gate structure 8 is attached to the crank portions 6 and 7 by means of eye bolts 9 and 10 which are likewise engaged with nuts 9' and 10' on opposite sides of the frame of the gate, whereby the bolts 9 and 10 may be adjusted with respect to the gate, said crank portions being so arranged that when the hinge rod 3 is given a partial turn, the outer end of the gate will be thrown upwardly, while the position of the crank portion 6 will incline the gate laterally and cause the same to rapidly swing to the right or left and to open position by gravity, depending upon the direction in which the hinge rod is rotated.

The outer end of the gate 8 is provided with a spring latch 11 which engages a notch 12 in a keeper 13 on the post 2, said latch being so arranged that when the outer end of the gate is elevated it will be lifted above and disengaged from the keeper, while the edge faces of the keeper are so curved that the latch will readily snap into the notch when the gate is again swung to its closed position. As shown in Figs. 1 and 2, the upper end of the hinge rod 3 may have attached thereto a plurality of arms 14, the outer ends of which are provided with forks 15 for engagement with a pull cable 16, said pull cable having a plurality of balls or knobs 17 attached thereto and arranged in pairs so that a ball will pass to either side of each fork and cause the hinge rod to rotate when a lengthwise pull is given to the cable.

The cable 16 is extended a predetermined distance on opposite sides of the line of fence and the ends thereof extended over sheaves 18 attached to the upper ends of the supporting posts 19, said ends of the cable being carried beyond the sheaves and attached to the outer ends of the levers 20, a sufficient length of the ends of the cable being extended beyond each lever to receive a ring 21, or similar device which may

be readily grasped to give a pull upon the cable.

The posts 19 have keepers 22 attached thereto which are constructed similar to the 5 keepers 13 and provided with notches 23 with which the latch of the gate engages when the gate is swung to an open position, said keepers also being provided with integral ears 24 between which the inner ends of 10 the levers are pivotally mounted. The levers 20 normally extend at an upward outward angle from their hinged ends so that the weight of the levers will hold the pull cable sufficiently taut to always hold the cable in 15 engagement with one of the forks and will retain the cable in position to successively engage the forks as said forks are moved into the path of the cable.

When the hinge rod has been given a 20 quarter turn the gate will assume the same relation with the hinge rod, as soon as it has swung to an open position, as it has with the rod when the gate is in closed position and consequently when the hinge rod is given a 25 reverse quarter rotation the gate will be caused to swing to closed position.

As shown in Figs. 3 and 4 of the drawings, a different form of device for attaching the cable to the hinge rod is shown and in this 30 instance a wheel 25 is attached to the upper end of the hinge rod 3, the periphery of the wheel having a groove or channel 26 in which a portion of the cable 16 is seated, said cable in this instance being extended 35 once around the wheel and to prevent the cable from slipping on the wheel any suitable form of securing means 27 is employed for attaching the cable to the wheel. When the wheel is used in connection with the rod 40 3 the cable may be made in one length or in two sections, if desired, the inner ends of the sections being disposed substantially half way around the wheel and anchored thereto. The remainder of the gate structure and the 45 operation of the same is exactly as that described in the preceding description and I hereby reserve the right to use either form of device for operating the gate rod or any preferred form of device as may come within the scope of my invention.

This form of structure, in view of its simplicity, may be very cheaply constructed and readily applied to use, and in view of

the construction of the crank portions of the hinge rod the gate will be very quickly 55 thrown to an open or closed position by gravity. And it will likewise be seen that in view of the arrangement of the levers and pull cable, the hinge rod can be very easily rotated to cause the gate to swing to an open 60 or closed position.

Having thus fully described my invention what I claim as new and desire to secure by Letters Patent of the United States, is:—

The combination with a hinge rod having oppositely disposed crank portions, and a gate attached to said crank portions, of a pull cable, means carried by said rod and coöperating with the cable to cause the hinge rod to rotate when the pull cable is moved 70 longitudinally in either direction, a supporting post a distance on each side of the gate supporting post, a sheave mounted upon the upper end of each supporting post and in alinement with the upper end of said rod, 75 the ends of said cable extending over said sheaves and a distance beyond the same, a keeper fixed to each supporting post a distance below the upper end thereof, a lever pivotally secured at one end to each keeper, 80 said levers extending upwardly at an obtuse angle to said supporting posts and having their upper ends attached to the ends of the cable a distance from said sheaves, said levers being at a uniform angle from the 85 posts when the gate is closed, and one of said levers resting substantially at right angles to the post and the other substantially parallel with its post when the gate is in open position, whereby the weight of said levers will exert tension on the cable at all times and hold the same taut, the ends of said cable projecting beyond the ends of the levers to form hand holes to be grasped when a downward pull is given to move the 90 cable endwise in either direction for opening or closing the gate, the downward movement of one lever giving an endwise thrust to the cable.

In testimony whereof I have signed my 100 name to this specification in the presence of two subscribing witnesses.

WILLIAM SHERMAN FLICK.
